(57) **CLAIM**

The ornamental design for a hammer drill, as shown and described.

DESCRIPTION

Cross reference is made to copending U.S. design patent application Ser. No. 29/865,623 entitled “Suction Attachment for a Power Tool” by Vincent Hasenmayer, which was filed on even date herewith.

FIG. 1 is a perspective view of a hammer drill showing my new design;

FIG. 2 is a front elevational view of the hammer drill of FIG. 1;

FIG. 3 is a rear elevational view of the hammer drill of FIG. 1;

FIG. 4 is a left side elevational view of the hammer drill of FIG. 1;

FIG. 5 is a right side elevational view of the hammer drill of FIG. 1;

FIG. 6 is a top plan view of the hammer drill of FIG. 1; and, FIG. 7 is a bottom plan view of the hammer drill of FIG. 1. The broken lines shown in the drawings depict portions of the hammer drill that form no part of the claimed design.
